UNITED STATES PATENT OFFICE.

CHARLES D. RICE, OF CORRY, PENNSYLVANIA.

ROLLER-SKATE.

SPECIFICATION forming part of Letters Patent No. 326,151, dated September 15, 1885.

Application filed April 4, 1885. (No model.)

To all whom it may concern:

Be it known that I, CHARLES D. RICE, a citizen of the United States, residing at Corry, in the county of Erie and State of Pennsylvania, have invented certain new and useful Improvements in Roller-Skates, of which the following is a specification, reference being had therein to the accompanying drawings.

My invention has relation to certain improvements in roller-skate clamping and truck-connecting devices; and it consists in the construction and novel arrangement of devices, whereby any side pressure upon one truck is transmitted to the other, and the clamping arms and lever are brought into a convenient position for adjustment by the wearer, and also by which the skate is adapted to receive boots of different sizes—for example, a wide sole and narrow heel, or a narrow sole and a large heel—as will be hereinafter more fully described, and specifically set forth in the claims.

In the accompanying drawings, Figure 1 is a side elevation of my improved skate with its clamping devices attached and its forward portion in vertical section. Fig. 2 is a bottom view of the same with the foot-clamps open, and its parallel rod partly broken away to show the spring-connection of the trucks. Fig. 3 is a bottom view of the foot-clamps closed and a horizontal section on line *y y* of Fig. 1. Fig. 4 is a vertical section on line *x x* of Fig. 1; and Fig. 5 is a rear view of my improved skate with the rollers in section.

Like letters refer to like parts in all the figures.

In the drawings, A represents the foot-plate, which can be made of steel, or of any suitable material, and to the underside of which are secured the upper castings or bearing-plates, A', of the trucks, by screws *a*', passing through the foot-plate A into the lugs or pillars A'' of said castings A'.

The front and rear trucks, B, are arranged to rock in opposite directions to each other, and are set wider apart at the bottom than at the top. Said trucks are provided with broad disk-bearing surfaces *b*, that permit free play of the parts.

The three pillars A'' of the casting A' form the points of a triangle, and fulfill a double service. They act as braces and supports for the foot-plate A, and as guides for the foot-

clamps to play between them. The lower portion of the casting A' is provided with a screw-threaded perforation, A³, and the upper portion is provided with an oil channel and chamber, A⁴, in line with and immediately below the perforation *a* in the foot plate, to receive oil, &c., to lubricate the disk-bearings *b*.

The casting B is provided with a slotted arm, B', in the upper portion thereof, to receive one end of a metal spring, C, and a pin or rivet, *b*', is inserted in the upper portion of said arm to keep the spring in place.

The lower portion of the casting B has a perforation, B², to receive one end of the rod D before it enters the perforation A³ of the bearing-plate A'. The perforation B² acts as journal-bearings for the roller-spindle F, and said bearings are provided with an oil chamber and channel, *b*², to lead the oil to the roller-spindle F.

The flat metal spring C has its upper edge concave, and extends from one truck to the other, and being simply held in position by the slotted arms B' and pins *b*', allows the trucks to yield laterally, as said spring C receives both a bending and a twisting strain.

The parallel rod D is located immediately below the flat spring C. It runs parallel with the foot-plate A until it enters the casting B of the trucks, where it takes a diagonally-upward course at both ends. The two ends D' are screw-threaded and pass through the trucks B, and are screwed into the perforation A³ until the casting B rests against the shoulder D'', formed upon the rod D'.

Midway of the parallel rod D is a clamp, D³, which is provided with a slot at its upper end, through which the metal spring C passes, and is held firmly in position by a clamping-screw, *d*, located on the side thereof. The clamp D³ straddles the parallel rod D and forms a central brace for the spring. The rod D does a treble service—it unites the working parts of each truck, strengthens the entire skate, and also furnishes a clamping-point for the spring.

The heel and sole clamps E are located under the foot-plate A and are connected by sheet metal links E' and E'' and the lever E³. Said clamps E pass above the casting A', between the pillars A'' thereof, and the latter act as guides for said clamps, which extend beyond the sides of the foot-plate A, where

their ends are inwardly beveled, as at e . The link E' is secured to the two forward clamps at one end by a pivot, e' , while at the other end it is united to the lever E^3 by a pivot, e^2 . One 5 end of said lever is bent down to form a pendent handle, e^3 , by which it can be swung from against the forward portion of the spring C toward the pendent pin a^2 . The lever E^3 is also provided with an eccentric stud-pin, e^4 , to 10 enter one of the perforations e^5 in one end of the metal link E^2 , to adjust the clamps to any size of shoes, and the opposite end is united to the two rear clamps by the pivot e^6 . By 15 these means the two links E' and E^2 are drawn together by the lever E^3 .

In Fig. 5 the roller-spindle F is shown as having a head, F' , at one end, and at the other end it is screw-threaded at F^2 to receive a thin nut, f , which is transversely perforated and 20 held in position by a pin, f' , passing through said perforations and spindle.

Oil poured through the perforations a in the foot-plate A will follow various channels leading to all the wearing-surfaces of the 25 skate.

Having now fully described my invention, I claim—

1. In a roller-skate, the combination of the truck-bearing A' , having a central oil-chamber, A^4 , and pillars A^2 , and the truck B , forming therewith a disk-bearing, b , the slotted arm B' , and transverse pin b' , with the foot-plate A , spring C , and parallel rod D , substantially as and for the purpose described.
2. In a roller-skate, the combination of the casting A' , provided with pillars A^2 and screw-threaded perforation A^3 , and the oil-chamber A^4 , with the casting B , provided 35

with a slotted arm, B' , rivet b' , journal-bearings B^3 , and oil-channel b^2 , substantially as 40 and for the purpose described.

3. In a roller-skate, the metal spring C , in combination with the rod D , clamp D^3 , and casting B , provided with slotted arm, substantially as and for the purpose described. 45

4. In a roller-skate, the rod D , provided with upwardly-bent screw-threaded ends D' , and shoulders D^2 thereon, and the clamping device D^3 , in combination with the spring C , the two castings A' and B , roller-spindle F , 50 and foot-plate, substantially as and for the purpose described.

5. In a roller-skate, the combination of the four clamps E , provided with upright ends e , links E' and E^2 , provided with perforations e^5 , 55 and lever E^3 , provided with eccentric stud-pin e^4 , substantially as and for the purpose described.

6. In a roller-skate, the clamp E , metal links E' , and E^2 , and lever E^3 , in combination 60 with the foot-plate A , castings A' , having pillars A^2 , trucks B , and rollers, substantially as and for the purpose described.

7. In a roller-skate, the foot-plate A , provided with perforations a at both ends thereof, in combination with the castings A' , and trucks B , provided with oil-channels A^4 and b^2 , substantially as and for the purpose described. 65

In testimony whereof I affix my signature 70 in presence of two witnesses.

CHARLES D. RICE.
